DISPLAY STAND

Joseph Palma, Jr., Berwyn, and James G. Knapp, Lombard, Ill., assignors, by mesne assignments, to American-Marietta Company, Chicago, Ill., a corporation of Illinois

Application January 19, 1955, Serial No. 34,066

Term of patent 14 years

(Cl. D80—9)

Fig. 1 is a perspective view of a display stand, showing our new design,

Fig. 2 is a front view in elevation,

Fig. 3 is a side view in elevation, and

Fig. 4 is a top plan view.

The perforations shown fragmentary in Figs. 1 and 2 are represented over the entire surface of the panels.

We claim:

The ornamental design for a display stand as shown and described.
